UNITED STATES PATENT OFFICE.

MARVIN SMITHEY, OF LAWRENCEVILLE, VIRGINIA, ASSIGNOR TO THE HAMILTON CORPORATION, OF LANCASTER, PENNSYLVANIA, A CORPORATION OF PENNSYLVANIA.

DESIGN FOR A FACE-PLATE OF MEASURING INSTRUMENTS OR METERS.

49,973.

Specification for Design.

Patented Nov. 28, 1916.

Application filed September 18, 1916. Serial No. 120,912. Term of patent 14 years.

To all whom it may concern:

Be it known that I, MARVIN SMITHEY, a citizen of the United States, residing at Lawrenceville, in the county of Brunswick and State of Virginia, have invented a new, original, and ornamental Design for the Face-Plates of Measuring Instruments or Meters, of which the following is a specifi-

cation, reference being had to the accompanying drawing, forming part thereof.

The figure in the drawing is a front view of the face plate embodying my design.

I claim—

The ornamental design for a face plate of measuring instruments, or meters, as shown.

MARVIN SMITHEY.
